AIR CONDITIONING APPARATUS

Reginald G. Wyld, Dayton, Ohio, assignor, by
mesne assignments, to Chrysler Corporation,
Highland Park, Mich., a corporation of Dela-
ware

Application August 7, 1937, Serial No. 157,932

2 Claims. (Cl. 62—6)

My present invention relates to an air conditioning apparatus, particularly relates to air conditioning units of medium capacity, although the identical apparatus may be used in connection with the smallest or the largest installations. The primary object of my invention is to create better conditions within the enclosure in which the unit is placed than has been possible with prior systems of comparable cost and simplicity. The object of my invention is to devise a simple unit without dampers, by-passes, control motors and other expensive and perhaps noisy equipment, thereby reducing the initial cost of the unit and making the unit less likely to fail.

In accordance with my invention I am able to obtain accurate control of conditions by utilizing a cooling coil through all of which all of the air being conditioned is passed at all times when the unit is in operation, and a part of which is removed from the circuit of the refrigerating medium in order to obtain closer control of the removal of latent or sensible heat from the air in accordance with the existing atmospheric conditions and the desired conditions.

The objects and advantages of my invention will be more readily apparent from the following specification taken in connection with the accompanying drawings in which Fig. 1 sets forth a schematic view of my system; Fig. 2 is an operating chart showing the performance of a unit having a certain size of coil connected to a certain size of compressor and operating in accordance with my invention; and Fig. 3 is a chart showing the operating range of my unit, the chart being drawn in accordance with the comfort chart devised by the Harvard School of Public Health.

Fig. 1 discloses an air conditioning unit 10 which may be of any capacity and may be of any type designed to condition atmosphere in an enclosure. The unit may be so mounted as to take air directly from the enclosure and direct the same back into the enclosure, or it may be connected thereto by ducts, and the incoming air may consist partly of fresh outside air and partly of recirculated air from the enclosure or may consist entirely of either. The unit comprises an evaporating coil 11 so positioned across the interior of the unit as to require all of the air to pass through all of the coil at all times when the system is in operation, the air being drawn through the coil by the blower 12 as schematically set forth. The coil is connected to a condensing unit consisting of a compressor 13 and a condenser 14 from which condensed

liquid passes through liquid pipe 15 into a header 16 having a plurality of branches 17, 18 and 19. Each header feeds refrigerant to a part of the coil 11 (each part being preferably approximately one-third of the coil). The refrigerant then enters the suction header 20 and returns to the compressor by way of the suction pipe 21.

The control of my system is accomplished by means of a circuit also set forth in schematic fashion in Fig. 1. The compressor 13 is operated by a compressor motor 30 receiving power from the power lines 31 when connected thereto through a switch 32. The blower is driven by a blower motor 33 receiving power from the power lines 34 when connected thereto through a switch 35. The blower motor may be set in operation by closing a manual switch 36 completing a circuit from positive side of power lines 34 through a solenoid 37 and back to negative side of power lines 34, the solenoid 37 being thereby energized to hold switch 35 in closed position. The blower may therefore operate independently of the compressing unit so that circulation of air may be accomplished with or without refrigeration. When the blower motor is operating a circuit to the compressor motor controls, which is connected to the blower circuit on the motor side of switch 35, may be energized. The compressor control circuit comprises a line 40 and a manual switch 41 which is preferably placed in juxtaposition to switch 36. The line 40 leads to a solenoid 42 which, when energized, holds switch 32 in closed position thereby causing the compressor to operate. When all conditions are satisfactory the solenoid 42 will be energized but the circuit can be disrupted by one or more control elements. The control circuit is completed to the power lines 34 through a line 43 which leads to the switch element 44 of a two-position thermostat T₁ (preferably of the snap-acting type well-known in the art). With such a thermostat, if the temperature passes beyond a set point toward the high side the contact T_H will be engaged and if the temperature passes below the set point the contact T_L will be engaged so that the circuit to solenoid 42 may be completed through one or the other of parallel lines 45 or 46. Line 45 leads to the solenoid 23 of a solenoid valve 22 placed in the branch 19 of header 16, the solenoid valve therefore being capable of suspending the flow of refrigerant into a part of the coil. The parallel line 46 includes a thermostat T and a humidostat H. Beyond the junction of lines 45 and 46 there is also placed a safety device or devices schematically represented by a high pressure cut-

off. The safety device may be a high pressure cut-off or a pressure relief valve. The safety device is connected to the power lines 34 through a line 47 which leads to the switch element 48 of a two-position thermostat T₂ (preferably of the snap-acting type well-known in the art). With such a thermostat, if the pressure passes beyond a set point toward the high side the contact T_H will be engaged and if the pressure passes below the set point the contact T_L will be engaged so that the circuit to solenoid 42 may be completed through one or the other of parallel lines 49 or 50. Line 49 leads to the solenoid 23 of a solenoid valve 22 placed in the branch 19 of header 16, the solenoid valve therefore being capable of suspending the flow of refrigerant into a part of the coil. The parallel line 50 includes a thermostat T and a humidostat H. Beyond the junction of lines 49 and 50 there is also placed a safety device or devices schematically represented by a high pressure cut-

out switch 47 under control of an expansion bellows 48 operated by pressure from the high pressure side of the refrigerating system through a connection 49.

5. If thermostat T_H is set at a high point such as 80° F. the low limit thermostat T should be set at a lower point such as 75° F. and the humidostat H may be set at the desirable position of 50% relative humidity. If the temperature passes 10. above 80° F. the thermostatic element 44 will contact T_H thereby energizing solenoid 23 to open solenoid valve 22 and admit refrigerant to all of the coil. The refrigerant is therefore evaporated into all the coil when the temperature passes 15. beyond a high limit, regardless of the vapor content of the atmosphere. If the temperature passes below 80° F. contact T_L will be engaged and solenoid valve 22 will close. As long as there is further demand for cooling and removal of 20. water vapor (the temperature remaining above the low limit of 75° F. and the humidity remaining above the low limit of 50% R. H.) the compressor will continue to operate but refrigerant will only be expanded into two-thirds of the 25. remainder of the coil fed through branches 17 and 18. Since the condensing unit is of a definite capacity the head pressure in discharge pipe 15 will remain constant but the back pressure in suction pipe 21 will drop. The compressor will 30. continue to operate under such conditions until either the temperature or the humidity passes below the low limits, or perhaps due to increasing occupancy load or outside temperature T_H may be re-engaged thereby throwing the entire 35. coil into operation. The high pressure cut-out will stop the compressor regardless of the atmospheric conditions if the compressor discharges more refrigerant than can pass through the coil.

In Fig. 2 there is set forth a chart of capacities 40. in which the ordinates represent tons of refrigeration and the abscissas represent suction temperatures of a certain system having a compressor of definite capacity and a coil of definite capacity. The line 50 represents the total capacity of the compressor in tons of refrigeration when connected to a coil creating a two inch pressure drop in the suction line. The line 51 represents the total capacity of a twelve inch coil having a certain face area and a certain number 45. of fins and tubes having certain dimensions when 4000 C. F. M. of air at 80° D. B., 50% R. H. is passed through the coil. These lines intersect at point 52 giving the total capacity of the unit as 50. 9.55 tons of refrigeration. The line 53 gives the proportion of the compressor capacity under the 55. conditions set forth which is devoted to sensible work or the lowering of the dry bulb temperature of the air being treated and line 54 gives the proportion of latent work or removal of heat of vaporization from the air. It can thus be seen that directly below point 52 the points 55 and 56 give 6.14 tons sensible and 3.41 latent tons at the full capacity of the system, and that all these points are on the line representing a suction temperature of 36 1/2°. Line 57 gives the capacity of two-thirds of the full coil and lines 58 and 59 give the capacities of one-half and one-third, respectively, of the coil. Line 57 crosses line 50 at point 60 giving the total load as 7.65 tons and a suction temperature of approximately 28°; points 61 and 62 giving sensible and latent loads of 4.65 tons and 3.00 tons, respectively. It can thus be seen that by reducing the effective face area of coil 11 emphasis is being given to the extraction of moisture from the air whereas with full capacity

the aim of the unit is to extract as much sensible heat as possible. Using the control limits set forth with respect to Fig. 1 and the capacities set forth with respect to Fig. 2 it can be seen that T_H will be contacted above 80° F. and the system 5 will operate under a total load of 9.55 tons with the ratio of latent to total at 35.7%. If the temperature drops below 80° F. T_L will be contacted and the system will operate under a total load of 7.65 tons with the ratio of latent to total at 39.4%. 10 The system will cease operating if the temperature drops below 75° F. or the humidity below 50% R. H.

Fig. 3 is based on the form of comfort chart developed by the Harvard School of Public Health 15 in which the ordinates are wet bulb temperatures in degrees Fahrenheit, the abscissas are dry bulb temperatures in degrees Fahrenheit, and the lines running diagonally upward from left to right represent relative humidities for the corresponding wet and dry bulb temperatures. The curved dash lines running diagonally downward from left to right represent effective temperatures or lines representing conditions of equal warmth and physical comfort when the air movement is 20. approximately 15 to 25 feet per minute. Under these conditions it has been determined that the summer comfort zone is between the limits of approximately 64° and 79°, effective temperature, and that between approximately 68° and 74°, 25. effective temperature, from 75% to 98% of the people will be comfortable, the ideal summer comfort line being at 71°, effective temperature. Of course department stores and theatres subject to varying loads and intermittent occupancy may 30. have a higher comfort line, and when the outside temperature varies the comfort line will also vary so that it has been determined that outside temperatures of 70° D. B. to 95° D. B. should be matched by inside comfort lines of 68° E. T. to 40. 73° E. T. Also a further limitation is placed upon the comfort zone in that very low relative humidities cause a feeling of dryness in the throat and nostrils and very high humidities prevent rapid removal of perspiration from the clothing, resulting in a feeling of dampness. A healthy condition of humidity is realized between the ranges of 30% R. H. to 70% R. H., with 50% R. H. as the ideal condition at all times. Accordingly the zone into which air should be brought is in 45. any event within the limits of the summer comfort zone; in order to satisfy over seventy five percent of the people it should be within the range represented by 68° to 74°, effective temperature; and in order to be truly comfortable 50. should be close to 50% relative humidity.

In Fig. 3 the line 100 is set at approximately 79° D. B. and represents the lower limit of operation of the full coil, which means that whenever the temperature is above line 100 T_H will be contacted and the full coil will operate. As soon as the temperature drops below 79° D. B. the system will operate on two-thirds coil until either the temperature drops to line 101 or the relative humidity drops to 50%. The lower limit of the unit therefore is represented by line 101 which extends from 100% to 50% R. H., then by the 50% R. H. line until line 100 is reached, and then downward along line 100. By way of example; if a unit is placed in a closed room having a certain definite load with the air at conditions represented by point A (the temperature at 90° D. B. and the humidity at 70% R. H.) the unit will operate at full capacity drawing the condition of the air downward as represented by the dash line ex- 65. 70. 75.

tending to points B and C. Theoretically the line should extend horizontally to the left and then downward along the 100% R. H. line, but any unit will perform some latent work at all times and 100% R. H. is hardly ever achieved. Point B is on line 100 showing the limit of operation of the full coil and point C is on line 101 showing the limit of operation of the entire unit as controlled by thermostat T. Line 10 D—E—F shows another performance curve wherein the air is brought from 86° D. B., 40% R. H. to 74° D. B., 65% R. H. and line GH shows another performance curve where the air is brought from 90° D. B., 20% R. H. to 79° D. B., 15 38% R. H. The lower limit line of the unit is shown as crossing the comfort line at approximately 30% R. H., then back across the comfort line at 50% R. H., then again across the comfort line at 70% R. H.; so that the lower limit of 20 operation is as close to the summer comfort line as can be achieved with simplified controls.

Having described the preferred embodiment of my invention and the operation thereof it should be obvious to those skilled in the art that the 25 same may assume modifications in arrangement and detail, the true scope of my invention being determined by the following claims.

I claim:

1. An air conditioning system comprising 30 a compressor-condenser-expander refrigeration system including a single compressor of fixed capacity and a plurality of expander coils served by said compressor and arranged in parallel with each other, an air conditioning unit comprising 35 a cabinet and air moving means in said cabinet, said expander coils being arranged side by side as a bank of coils extending across the interior of the cabinet so that each of said expander coils is in the path of a part only of the total stream 40 of air moved through the unit by said air moving means and so that all of the air being treated moves through said bank of coils, a high limit thermostat arranged to open when the temperature of the air decreases below a high limit, 45 means responsive to the opening of said high limit thermostat to suspend the flow of refrigerant through one of said expander coils whereby to reduce the number of coils having effect in order materially to reduce the sensible heat removal capacity of the system and to lower the 50 temperature of the refrigerant leaving the remainder of the bank of coils in order to maintain the latent heat removal capacity of the system substantially constant, and a control circuit for 55 said compressor including circuit completing

means engaged by said high limit thermostat upon opening, a humidostat and a low limit thermostat arranged in series whereby the flow of refrigerant through all of said expander coils is suspended due to cessation of operation of said 5 compressor if the temperature of the air drops below a predetermined low limit so that said low limit thermostat opens or if the humidity of the air becomes such as to cause said humidostat to open while said high limit thermostat is in open 10 position.

2. An air conditioning system comprising a compressor-condenser-expander refrigeration system including a single compressor of fixed capacity and a plurality of expander coils served 15 by said compressor and arranged in parallel with each other, an air conditioning unit comprising a cabinet and air moving means in said cabinet, said expander coils being arranged side by side as a bank of coils extending across the interior of 20 the cabinet so that each of said expander coils is in the path of a part only of the total stream of air moved through the unit by said air moving means and so that all of the air being treated moves through said bank of coils, a high limit 25 thermostat arranged to open when the temperature of the air decreases below a high limit, means responsive to the opening of said high limit thermostat to suspend the flow of refrigerant through one of said expander coils whereby 30 to reduce the number of coils having effect in order materially to reduce the sensible heat removal capacity of the system and to lower the temperature of the refrigerant leaving the remainder of the bank of coils in order to maintain 35 the latent heat removal capacity of the system substantially constant, and a control circuit for said compressor comprising one branch having said high limit thermostat therein, and a parallel 40 branch including a contact engaged by said high limit thermostat upon opening movement thereof, a humidostat arranged to open if the humidity passes below a predetermined low limit, and a low limit thermostat arranged to open if the 45 temperature passes below a predetermined low limit, said contact, humidostat and low limit thermostat being arranged in series whereby the compressor stops operation and refrigerant ceases flowing through any of said expander coils if either the temperature of the air passes below a 50 predetermined low limit or the humidity of the air passes below a predetermined low limit while said high limit thermostat is in open position.

REGINALD G. WYLD. 55
